F. ALBACH

LOCKING MECHANISM FOR LOCKERS

Filed April 16, 1927.

FIG. 2.

FIG. 1.

FIG. 3.

FIG. 4.

INVENTOR:

FRANK ALBACH,

BY

Robert Burns.

ATTORNEY.

UNITED STATES PATENT OFFICE.

FRANK ALBACH, OF ST. LOUIS, MISSOURI, ASSIGNOR TO FRED MEDART MANUFACTURING COMPANY, OF ST. LOUIS, MISSOURI, A CORPORATION OF MISSOURI.

LOCKING MECHANISM FOR LOCKERS.

Application filed April 16, 1927. Serial No. 184,266.

This invention relates to that type of locking mechanisms for sheet metal lockers, used in offices, club rooms, etc., and more particularly to that type of such locking mechanisms in which the tumbler locking mechanism, operating handle and connections have a sliding movement as a whole in and on the locker door, in the operations of locking and unlocking said door, with the complementary operation of the latching bolts of the locker door. The present improvements have for their object:

To provide a structural formation and combination of parts by which operative connection between the latching mechanism and the slidable operating handle is attained, in a simple, substantial and effective manner, with an accurate guidance of the parts on and in the locker door, and with a simple and effective engagement between the plate metal body of the locker door, and the transversely sliding locking bolt of a cylinder lock mechanism mounted in the slidable operative handle of the latching mechanism, all as will hereinafter more fully appear.

In the accompanying drawing:

Fig. 1, is a detail vertical elevation, with parts in section on line 1—1 Fig. 3, illustrating the preferred form of the present locking and latch operating mechanism for locker or cabinet doors.

Fig. 2, is a detail rear elevation of the same.

Fig. 3, is a similar view, with the rear guard or cover plate removed.

Fig. 4 is a detail horizontal section on line 4—4 Fig. 1.

Like reference numerals indicate like parts in the different views.

In the construction shown, the locker or cabinet door 1, is formed of plate metal reinforced by the usual marginal or border flange 2, and adjacent to a vertical portion of said border flange the panel or main body

of the door is formed with a pair of vertically elongated orifices 3 and 4 in spaced relation and in which the guide extensions 5 and 6 of the hereinafter described operating handle or bail has sliding movement.

In the present improvement the upper and main orifice 3 aforesaid, is formed with in-turned marginal flanges 3' at its respective sides to afford increased bearing and guiding surfaces for the above mentioned guide extension 5 of the operating handle, but

more especially to afford material or metal for the formation of aligned notches 7 for the reception of one or the other ends of the transversely sliding bolt 8 of the hereinafter described cylinder lock mechanism 60 which is mounted in the operating handle or bail, and with said bolt 8 adapted by engagement in one or the other of the notches 7 to lock said handle or bail against vertical movement. The lower and auxiliary 65 guide orifice 4 is usually of a flangeless formation as shown, in that as so formed it affords ample bearing and guiding surface for the guide extensions 6 of the operating handle.

The operating handle above referred to, is of the bail type, with its arch shaped, central or grip portion 9, merging at one end into an upper head portion or hub 10, the base of which is of an expanded form as 70 shown for sliding contact on the outer face of the locker door 1 and constitutes a cover concealing the guide orifice thereof. The guide extension 5, heretofore mentioned, is formed integral with the head or hub 10 and 75

the expanded base of the same, and extends inwardly for sliding and guiding engagement in the vertical door orifice 3 aforesaid. The other end of the central or grip portion 9 of the operating handle merges into a 80 lower head portion or hub 11, the base of which is of an expanded form for sliding contact on the outer face of the locker door 1 and adapted to cover and conceal the guide orifice 4 of said door. The heretofore men- 85

tioned guide extension 6 is formed integral with the head or hub 11, and extends inwardly therefrom for sliding and guiding engagement in the vertical door orifice 4 aforesaid. Said extension 6 is formed with 90 a screw threaded orifice for the reception of a screw bolt 12, by which the hereinafter described cover and confining plate 13 is fixedly connected to said extension.

The upper head portion or hub 10, and 100 the guide extension 5 thereof, above referred to, is of a tubular formation so as to provide a central bore formed to receive and house any usual and suitable type of cylinder lock mechanisms, with the revoluble 105 barrel 10' of said cylinder lock mechanism having operative connection by an eccentrically arranged stud 8' on the inner end of the barrel 10' in operative engagement in a cross slot in the mid-length of the afore- 110

said locking bolt 8 as shown in Fig. 4. In the present construction the locking bolt 8 is mounted in a transversely extending guide groove formed therefor in the rear 5 end of said guide extension 5 of the operating handle, with said bolt 8 adapted for locking engagement in one or the other of the heretofore described notches 7 of the marginal flanges 3' of the locker door orifice 3, in accordance with the direction in which the cylinder lock mechanism is turned.

The rear cover and confining plate 13 above referred to, is formed of plate metal, with its upper portion having a channel 15 formation so that its respective side webs or flanges may have sliding and guiding contact with the respective side flanges of the inturned marginal flange 3' of the guide orifice 3 of the locker door. Said plate 13 has fixed attachment at its upper end with the aforesaid guide extension 5 by one or 20 more attaching screw bolts 14.

The lower portion of the cover and confining plate 13, is of a flat form and has 25 fixed attachment to the lower guide extension 6 by the screw bolt 12 heretofore described.

In the present locking and latching or bolt operating mechanism of the locker door 30 1, the primary operating lever or arm 15 of the latching means will be operatively connected to the aforesaid cover and confining plate 13, in any suitable manner, preferably by means of the attaching screw 12 by which 35 the lower portion of the plate 13 is attached in place.

Having thus fully described my invention, what I claim and desire to secure by Letters Patent, is:—

40 1. In a locking and latch operating mechanism for locker doors, the combination of a locker door provided with an elongated guide orifice having holding notches at its respective sides, a slidably mounted operating handle provided with an inwardly extending guide extension adapted for movement in the guide orifice of the locker door, said guide extension having a transversely arranged guide slot at its rear end, a trans- 45 verse bolt having movement in said guide slot and adapted for locking engagement in a side notch of the locker door orifice aforesaid, said transverse bolt forming a member of a lock mechanism arranged in the 50 guide extension of the handle, and means for holding said operating handle in position on the locker door, said handle being adapted for operative engagement with the latching means of the locker door.

60 2. In a locking and latch operating mechanism for locker doors, the combination of a locker door provided with an elongated guide orifice having an inturned border flange having holding notches in the respective sides of the flange, a slidably mounted

operating handle provided with an inwardly extending guide extension adapted for movement in the guide orifice of the locker door, said guide extension having a transversely arranged guide slot at its rear end, 70 a transverse bolt having movement in said guide slot and adapted for locking engagement in a side notch of said border flange of the aforesaid door orifice, said transverse bolt forming a member of a lock mechanism 75 arranged in the guide extension of the handle, and means for holding said operating handle in position on the locker door, said handle being adapted for operative engagement with the latching means of the 80 locker door.

3. In a locking and latch operating mechanism for locker doors, the combination of a locker door provided with a pair of elongated guide orifices in spaced relation, one of said orifices having holding notches in its respective sides, a slidably mounted operating handle provided with a pair of inwardly extending guide extensions in spaced relation for movement in the guide orifices aforesaid, one of said guide extensions having a transversely formed guide slot in its rear end, a transverse bolt having movement in said guide slot and adapted for locking engagement in a side notch of the locker door orifice aforesaid, said transverse bolt forming a member of a lock mechanism arranged in the guide extension of the handle, and means for holding said operating handle in position on the locker door, said handle being adapted for operative engagement with the latching means of the 90 locker door.

4. In a locking and latch operating mechanism for locker doors, the combination of a locker door provided with a pair of elongated guide orifices in spaced relation, one of said orifices having an inturned border flange formed with holding notches in its respective sides, a slidably mounted operating handle provided with a pair of inwardly extending guide extensions in spaced relation for movement in the aforesaid guide orifices, one of said guide extensions having a transversely formed guide slot at 105 its rear end, a transverse bolt having movement in said guide slot and adapted for locking engagement in a side notch of a border flange of the aforesaid door orifice, said transverse bolt forming a member of a lock mechanism arranged in the guide extension of the handle, and means for holding said operating handle in place on the locker door, said handle being adapted for operative engagement with the latching 110 means of the locker door.

5. In a locking and latch operating mechanism for locker doors, the combination of a locker door provided with an elongated guide orifice having holding notches at its 120

- respective sides, a slidably mounted operating handle provided with an inwardly extending guide extension adapted for movement in the guide orifice of the locker door, 50
 5 said guide extension having a transversely arranged guide slot at its rear end, a transverse bolt having movement in said guide slot and adapted for locking engagement in a side notch of the locker door orifice aforesaid, one of said guide extensions having a transversely formed guide slot in its rear end, a transverse bolt having movement 55
 10 said guide slot and adapted for locking engagement in a side notch of the locker door orifice aforesaid, said transverse bolt forming a member of a lock mechanism arranged in the guide extension of the handle, and means for holding 60
 15 said operating handle in position on the locker door, the same comprising a confining plate secured to the rear end of the aforesaid guide extension of the operating handle and adapted for operative connection with the latching means of the locker door. 65
 20 6. In a locking and latch operating mechanism for locker doors, the combination of a locker door provided with an elongated guide orifice having an inturned border flange having holding notches in the respective 70
 25 sides of the flanges, a slidably mounted operating handle provided with an inwardly extending guide extension adapted for movement in the guide orifice of the locker door, said guide extension having a transversely arranged guide slot at its rear end, a transverse bolt having movement in said 75
 30 guide slot and adapted for locking engagement in a side notch of said border flange of the aforesaid door orifice, said transverse bolt forming a member of a lock mechanism arranged in the guide extension of the handle, and means for holding said handle in position on the locker door, the same comprising a confining plate secured to the rear end of the aforesaid guide extension of the operating handle and adapted for operative connection with the latching means of the locker door. 80
 35 7. In a locking and latch operating mechanism for locker doors, the combination of a locker door provided with a pair of elongated guide orifices in spaced relation, one of said orifices having holding notches in its 85
 40 45 respective sides, a slidably mounted operating handle provided with a pair of inwardly extending guide extensions in spaced relation for movement in the guide orifices aforesaid, one of said guide extensions having a transversely formed guide slot in its rear end, a transverse bolt having movement 90
 50 in said guide slot and adapted for locking engagement in a side notch of the locker door orifice aforesaid, said transverse bolt forming a member of a lock mechanism arranged in the guide extension of the handle, and means for holding said operating handle in position on the locker door, the same comprising a confining plate secured to the rear ends of the aforesaid guide extensions of the operating handle and adapted for operative connection with the latching means of the locker door.
8. In a locking and latch operating mechanism for locker doors, the combination of a locker door provided with a pair of elongated guide orifices in spaced relation, one of said orifices having an inturned border flange formed with holding notches in its respective sides, a slidably mounted operating handle provided with a pair of inwardly extending guide extensions, in spaced relation for movement in the aforesaid guide orifices, one of said guide extensions having a transversely formed guide slot at its rear end, a transverse bolt having movement 95
 55 in said slot and adapted for locking engagement in a side notch of said border flange of the aforesaid door orifice, said transverse bolt forming a member of a lock mechanism arranged in the guide extension of the handle, and means for holding said operating handle in place on the locker door, the same comprising a confining plate secured to the rear ends of the aforesaid guide extensions of the operating handle and adapted for operative connection with the latching means of the locker door.

Signed at St. Louis, Missouri, this 14th day of April, 1927.

FRANK ALBACH.
